UNITED STATES PATENT OFFICE.

WALTER P. MURPHY, OF CHICAGO, ILLINOIS.

CAR-ROOF.

1,156,617.

Specification of Letters Patent. Patented Oct. 12, 1915.

Original application filed December 22, 1911, Serial No. 667,297. Divided and this application filed April 10, 1915. Serial No. 20,393.

To all whom it may concern:

Be it known that I, WALTER P. MURPHY, a citizen of the United States, and a resident of the city of Chicago, in the county of Cook and State of Illinois, have invented a new and useful Improvement in Car-Roofs, of which the following is a specification.

This invention relates to car roofs composed of individual roof sheets which are spaced side by side and are connected by means of seam covers, and is a division of my patent application for improvements in metal car roofs, Ser. No. 667,297, filed Dec. 22, 1911.

The object of this invention is an improved seam or joint for connecting movably mounted roof sheets; and a further object is an improved roof sheet for use in car roofs having flexible joints between the roof sheets.

The invention consists in the parts and arrangements hereinafter described, and is more particularly defined in the appended claims.

In the drawings, wherein is illustrated the preferred form of the invention, Figure 1 is a plan view of a portion of a car roof, a portion of the roof being removed to disclose the parts beneath; Fig. 2 is a transverse section through the ridge portion of the same, on the line 2—2 in Fig. 1; Fig. 3 is a side elevation of a portion of the roof at the eaves, showing the eaves end of a seam cover; Fig. 4 is a transverse section through the eaves portion of the roof on the line 2—2 in Fig. 1; Fig. 5 is a cross-section through a joint embodying the invention on the line 5—5 in Fig. 1; and Fig. 6 is a perspective view of a roof sheet.

The invention is applicable to outside metal roofs for cars having either metal or wood frame members. The roof substructure may be of any suitable construction. Preferably it consists of carlines 11 supported at their ends by the side plates 12 of the car, and purlins 13 and ridge piece 10 arranged lengthwise of the car and supported by the carlines. The roof sheets 14 are made from corrugated metal sheets, and are formed with upstanding side flanges 15 which are provided with inturned lips 16 at the top. The corrugations are flattened out at the eaves, and the eaves ends of the roof sheets 14 are turned down to form eaves flanges 17.

The roof sheets are "dished" between their side flanges, that is, the marginal portions 18 of the roof sheets adjacent to the flanges 15 are inclined upwardly, and are raised above the substructure where they meet the side flanges. Inverted channel-shaped seam covers 19 straddle the side flanges of adjacent roof sheets, the inside width of the seam covers being sufficient to leave a space between each side wall 20 thereof and the edge of the adjacent inturned lip 16. The side walls of the seam covers slope outwardly, and have lateral outturned base flanges 21 along their lower edges. The lateral base flanges 21 of the seam covers are disposed at a slight slant, conforming to the slant of the marginal portions 18 of the roof sheets, and are arranged to rest or bear flatwise on the roof sheets between the corrugations and side flanges of the sheets.

In the preferred form of the invention, the lateral base flanges 21 of the seam covers are pressed down on the slanting marginal portions 18 of the roof sheets to form watertight resilient flexible joints. Spacing the slanting marginal or dished portions of the roof sheets above the substructure eliminates any trouble due to the seam covers pinching the roof sheets down on the substructure and preventing the slight shifting of the roof sheets to accommodate themselves to distortion of the substructure. Moreover, the raised marginal portions of the roof sheets upon which the lateral base flanges of the seam covers rest are above the general water level of the roof sheets, and hence there is no liability of water seeping under the seam covers by capillarity and rusting out the roof sheets near their side flanges. There is sufficient spring in the seam cover flanges and in the upwardly inclined marginal portions of the roof sheets to keep them in close contact at all times, and to maintain the tightness of the joint even though the roof sheets may become displaced from their normal positions. Moreover, the pressure of the seam covers on the inclined marginal portions of the sheets has a tendency to maintain the sheets in their normal positions parallel to the carlines. This shape and arrangement of seam covers and roof sheets not only provides a watertight seam or joint between adjacent roof sheets well adapted to prevent the entering of water into the car, and one in which water

and cinders will not collect, but also provides a flexible means for retaining the sheets in normal position on the car.

The eaves ends 22 of the side seam covers 5 are turned down over the eaves, covering the ends of the carlines and the eaves corners of the roof sheets, and are spaced away from the fascias sufficiently to allow slight freedom of movement of the corners of the 10 roof sheets crosswise of the roof. The down-turned ends of the seam covers are loosely secured to the side of the car by bolts 23 which also attach the fascias to the side plates. The bolts 23 pass through holes in 15 the ends of the seam covers larger than the bolts and bushings 24 are placed on the ends of the bolts between the fastening nuts 25 and fascia board 26 for the purpose of spacing the nuts from the fascia and allowing 20 freedom of movement of the seam covers crosswise of the car.

The ridge ends of the roof sheets rest upon the ridge piece 10 and have upstanding flanges 27 which terminate in inturned lips 25 28 along their top edges. The ridge covers 29 straddle and cover the ridge flanges of each pair of oppositely arranged sheets. Corner caps 30 are arranged over the ridge ends of the seam covers 19 and ends of the 30 ridge covers 29, and the running board saddles 31 are arranged on top of the corner caps and bolted to the ridge piece thereby securing the corner caps and seam covers in position at the ridge.

35 The invention is not restricted to the precise forms and arrangements of parts shown and described.

What I claim is:

1. An all steel car roof comprising side 40 plates, carlines having vertical stiffening members, purlins attached to the bottoms of said carlines with their tops below the tops of the carlines, a ridge piece secured to the carlines, and dished flanged roof sheets arranged on said purlins between the carlines with their margins spaced from the latter, said roof sheets being supported intermediate their side margins on said side plates, purlins and ridge piece, and seam covers 45 50 straddling said carlines and roof sheet flanges and having downturned side walls resting flatwise on the dished portions of said roof sheets.

2. A car roof comprising side plates, carlines, purlins and a ridge piece, and flanged roof sheets dished upwardly at their side margins arranged between the carlines with their flanges spaced from the latter, said roof sheets supported on said side plates, purlins 55 and ridge piece and non-rigidly attached to the car by resilient means coöoperating with their dished margins within their flanges.

3. An all steel car roof comprising carlines, purlins, and ridge piece, dished roof 60 sheets having integral side and ridge flanges 65

non-rigidly supported on said purlins and ridge piece between the carlines, and retaining strips having flanged portions bearing upon the dished portions of said roof sheets substantially as described.

4. A car roof comprising a substructure, metal roof sheets thereon extending from the eaves toward the ridge, metal seam covers overlying the adjacent side margins of said sheets and means for securing the same to 75 the roof substructure, said sheets being provided with dished side marginal portions and upstanding flanges along their side edges and with upstanding corrugations adjacent to said marginal portions, said seam 80 covers being longitudinally formed to receive said flanges beneath the same, the sides of said seam covers terminating in lateral flanges resting on said dished side marginal portions of the sheets.

5. A car roof having a substructure comprising carlines, roof sheets supported on said substructure and having upstanding edge flanges with their extremities bent down, the margins of said roof sheets adjacent to said flanges being raised clear of the general plane of the roof sheets and overlapping the carlines and spaced therefrom, and seam covers spanning said edge flanges and having edge portions coöperating with 95 said raised margins for holding said roof sheets in position.

6. A car roof having a substructure, roof sheets supported on said substructure and having upstanding edge flanges, the margins 100 of a roof sheet adjacent to its upstanding flanges having an upward slope away from the body portion of said roof sheet, seam covers for the joints between adjacent roof sheets, the edges of said seam covers having a downward and outward slope 105 conforming to the slope of the margins of said roof sheets, and means for clamping said seam covers down on said substructure whereby said roof sheets are held in position thereon.

7. In a car roof, roof sheets movably arranged with their side margins contiguous and extending transversely with respect to the car, said side marginal portions of the 115 roof sheets being formed with upstanding flanges, the edge portions of the roof sheets sloping up to the bases of these flanges, said edge portions being spaced above the roof substructure and seam covers having slanting sides and lateral base flanges at an angle thereto conforming to the slope of the edge portions of the roof sheets overlapping the margins of adjacent sheets and secured to the roof substructure.

8. In a car roof, longitudinally corrugated roof sheets arranged side by side with the corrugations extending transversely with respect to the car, said roof sheets having upwardly sloping side edges terminating in up- 120 125

standing flanges, seam covers spanning said upstanding flanges, said seam covers having downwardly extending sides terminating in lateral flanges projecting at an angle there-to, said lateral flanges resting flatwise on the sloping side edges of the roof sheets between the corrugations and the upstanding side flanges thereof.

9. In a car roof, longitudinally corrugated 10 roof sheets movably arranged side by side and spaced apart with the corrugations extending transversely with respect to the car, said roof sheets having upwardly sloping side edges terminating in upstanding 15 flanges, seam covers spanning the spaces between adjacent roof sheets and covering said upstanding flanges, said seam covers having downwardly extending sides spaced from said upstanding flanges and terminating in 20 lateral flanges projecting at an angle there-to, said lateral flanges resting flatwise on the sloping side edges of the roof sheets between the corrugations and the upstanding side flanges thereof.
10. A seam construction for a car roof having movable roof sheets, said seam construction comprising a seam cover of inverted channel shape provided with outwardly projecting flanges along the lower 25 edges of its side walls, in combination with the side margins of the roof sheets, said side margins being raised to a height above the supporting substructure and provided with edge flanges projecting up within said seam 30 covers and spaced from the side walls thereof, the adjacent raised margins contacting 35 flatwise with the under surface of the out-

wardly projecting flanges of the seam covers, whereby a tight sliding joint is maintained between said seam covers and roof 40 sheets above the general level of the main drainage portion of said sheets.

11. A car roof comprising metal roof sheets arranged side by side with a clear space between them, said roof sheets having 45 their side margins raised above the plane of support of the roof sheets and clear of the supporting substructure, seam covers bridging the spaces between said roof sheets and having lateral flanges resting flatwise on 50 said raised margins, said lateral flanges terminating short of the junctions of the raised margins and the roof sheets, whereby a tight joint is maintained between said seam covers and roof sheets above the general 55 level of the main drainage portion of said roof sheets.

12. A car roof comprising a substructure, roof sheets arranged transversely on said substructure and movably supported thereon, said sheets being spaced apart at their sides, the side marginal portions of said sheets being raised above the general drainage level of said sheets and having upstanding flanges at the edges thereof, and seam 60 caps of inverted channel-shape bridging said upstanding flanges of the roof sheets and themselves having marginal flanges that bear flatwise against the raised marginal portions of the roof sheets.

Signed at St. Louis, Missouri, this 5th day of April, 1915.

WALTER P. MURPHY.
